AIR-VENTING VALVE FOR HOT-WATER SYSTEMS

John Upton, Cambridge, and Warren T. Ferguson,
Waban, Mass., assignors to Anderson Products,
Inc., Cambridge, Mass., a corporation of Massachusetts

Application March 26, 1941, Serial No. 385,234

14 Claims. (Cl. 137—122)

This invention relates to hot water heating systems and is particularly concerned with a means and method of eliminating trapped air from radiators, or such other places as it may accumulate.

In hot water heating systems, at the outset of operation there is always a certain amount of air distributed throughout the water. After a period of use, this air gradually collects in the upper portions of the system and particularly in the tops of the radiators. Those radiators that are on the upper floors usually accumulate more air than those down below.

If the system has a gravity expansion tank located above the highest radiator, a slight amount of the air will escape through this outlet, but the largest portion of the air becomes trapped in the various radiators.

In the sealed hot water systems which utilize an expansion tank, the trapped air similarly accumulates in the radiators so that the problem is present in both types of systems.

As air accumulates in a radiator, the heating efficiency is diminished as the water content is reduced. Therefore, it is essential that the air be eliminated so that the radiators may remain substantially full.

Heretofore it has been customary to eliminate air from the radiators periodically through the use of a manually controlled valve. Hot water radiators ordinarily have a small needle valve located at the top which may be opened to permit the escape of air as it may be necessary.

Many attempts have been made to provide a valve which will automatically vent air as it may accumulate in a radiator and at the same time prevent any escape of water.

One of the objects of the invention, therefore, is to provide a valve which may be attached to a hot water radiator to automatically vent air from the upper portions thereof as it may accumulate, without permitting the escape or overflow of water. Similarly, such a valve could be used at any other point where air might be trapped.

Another object of the invention is to provide a valve which will operate automatically from time to time to permit the escape of air from the radiator at a rate greater than the rate of air accumulation, so that if the valve is attached to a radiator which is, say, only half full of water, the air will be vented therefrom gradually by the intermittent operation of the valve. This assumes, of course, that sufficient water pressure is in the system to force the water upwardly in the radiator.

Another object of the invention is to provide a

special fitting whereby the valve may be suitably connected to a radiator, the fitting including a manually operated valve mechanism which will permit quick venting of the air from the radiator at the time of initially filling the system or at the start of the heating season and before the automatic valves are placed in operation.

The invention also contemplates the series of steps that take place in each heating cycle to result in the expulsion of the trapped air little by little as the cycles are repeated.

Another object of the invention is to provide an air venting valve which will operate successfully to vent air from all radiators regardless of location.

These and other objects of the invention will become more apparent as the description proceeds with the aid of the accompanying drawings, in which

Fig. 1 is a diagrammatic showing of a typical gravity hot water heating system utilizing a closed or sealed expansion tank;

Fig. 2 is a cross-section of the automatic venting valve;

Fig. 3 is a cross-sectional detail of the valve connection;

Fig. 4 is an enlarged detail of the valve members, showing the parts in normal, non-venting position;

Fig. 5 is an enlarged detail of the valve members with the parts in the position assumed at the end of the upward movement of the movable valve member and float;

Fig. 6 is an enlarged detail of the valve members with the parts in the position assumed just prior to venting;

Fig. 7 is an enlarged detail of the valve members with the parts in venting position;

Fig. 8 is a modified form of valve;

Figs. 9, 10 and 11 are detailed showings of the valve action in venting air and correspond to Figs. 5, 6 and 7.

Fig. 12 is another modification of the valve construction.

In Fig. 1 a boiler, represented at 2, is fired by any convenient source of heat, which in the present instance is shown as an oil burner 3. Boiler 2 has extending therefrom a riser 4 branching out into header 6, which in turn extends to two risers 8 and 10. Connected to risers 8 and 10 are radiators 12 and 14 respectively. From both of the radiators extend return lines 16 and 18, joining in a common return 20 at the lower part of the boiler. A sealed expansion tank 22 is connected to header 6 by pipe 24.

On each of radiators 12 and 14 is an automatic

venting valve 26 which will hereinafter be described in more detail. These valves 26 are connected to the radiators by a special connection 28 which will likewise be more fully described hereinafter.

In the operation of a system of this type, water from a feed line 30 is admitted to the boiler by valve 31 and the entire system is gradually filled as air is vented through the special connections 28. When radiators 12 and 14 have been filled, special connections 28 are closed and the system is sealed. In the meanwhile, during filling, water has flowed into compression tank 22 until the pressure of air in the top portion of the tank balances the water pressure to maintain the water in the topmost portions of the system.

With the system in this condition, it is ready for operation. The heating mechanism 3 in the typical instance will be automatically started and stopped through the suitable location of a thermostatic room control of the usual well-known type.

As the water, in response to the thermostat, is periodically heated, it circulates through the mains 4, 6, 8 and 10 to the radiators and returns to the boiler through return main 20 for re-heating and recirculation. Such expansion of the water as may take place during a heating cycle is provided for through the operation of compression tank 22 in which the air above the water surface is compressed as much as necessary. The system as described would operate indefinitely were it not for the fact that after a time the air in the water gradually rises and accumulates in the upper portion of the radiators, and as this happens, the heating efficiency is lowered. Therefore, it is essential that the trapped air be vented from time to time, and through the use of valves 26 this result is fully accomplished.

Referring now to Fig. 2, the valve construction will be more particularly described. The valve comprises a base 40 having a downwardly extending threaded nipple 42 adapted to make connection with the radiator. The base is circular and terminates in a flange 44 recessed at 46 to receive a gasket 48 on which rests flange 50 of a covering shell 52. Flange 50 is held tightly in place by lock nut 54 which is in screw threaded engagement with the base, as shown. Shell 52 has an opening at 56 for the escape of air to the atmosphere.

In screw threaded engagement with the interior of the base is a perforated supporting plate 58 arranged to permit free travel of air therethrough. The central portion of the plate is threaded at 60 to carry a correspondingly threaded adjusting screw 62. This screw is slotted at 64 to receive the end of a screw driver whereby easy adjustment may be made.

On base plate 58 is mounted a shell 66. The interior of this shell is divided into upper and lower portions by means of a ring 68 soldered or otherwise secured to the interior circumference and a bellows 70 mounted thereon. Bellows 70 is closed at its upper end by a member 72 of particular construction. Through the center of member 72 is a passage 74 which terminates at its lower and upper ends to form valve seats 76 and 78. The upper portion of shell 66 has a port 80 located at any convenient place therein.

It is apparent that any air entering through nipple 42 must pass through base plate 58, the lower portion of shell 66, through port 76, then

through port 80 of shell 66 and port 56 of shell 52 before it can finally reach the atmosphere.

Two valve members 82 and 84 are arranged for engagement with valve seats 76 and 78 respectively. Valve member 82 is mounted on the upper end of a diving bell type float 86. This float is contracted sufficiently at its upper end as at 88 to fit within the confines of the interior of bellows 70. The lower portion of the float is expanded as at 90 to provide improved float action. Float 86 is in turn supported on the upper end of adjustable stem 62.

Valve member 84, which depends downwardly toward valve seat 78, is carried by support 92, which is adjustably mounted at the top of shell 66 by threaded engagement therewith as shown.

In order that this valve may operate to vent air, it is necessary that there be a particular adjustment of valve members 82 and 84 with relation to the lower and upper valve seats 76 and 78. The method of adjustment is as follows: Valve member 84 is moved upwardly until it is entirely clear of valve seat 78. Stem 62 is then screwed upwardly, carrying with it float 86 and valve member 82 until the latter is very close to valve seat 76 or in actual engagement with it. If the adjustment is such that there is a slight clearance between valve pin 82 and seat 76, the pressure within the valve, that is normally present during operation, will result in driving float 86 and valve pin 82 upwardly into closed position. If, on the other hand, the adjustment is such that valve pin 82 is actually in engagement with valve seat 76, then, of course, the valve is normally closed at all pressures. The operation of the valve is the same regardless of this initial setting, because the float will always lift to closed position under normal operating conditions. The setting of valve member 72, as determined by the position of valve pin 82, controls the pressure necessary within the lower part of shell 66 before further elongation of bellows 70 can take place.

With this accomplished, support 92 is then screwed downwardly until valve member 84 is within a very small distance of valve seat 78, as in Fig. 4. It will be seen by this arrangement that under conditions of low pressure within the valve, port 14 will be normally closed by engagement of valve member 82 with valve seat 76. If the water level in the radiator has dropped, it is obvious that the interior of shell 66 will contain air only and there will be no buoyant effect on float 86. During the heating part of the heating cycle, the water in the system expands and this in turn results in an increase in pressure in the trapped air. The adjustment of stem 62 is such that the increased air pressure within the lower part of shell 66 during a heating cycle will be sufficient to cause further elongation of bellows 70, driving member 72 upwardly until valve seat 78 is in engagement with valve member 84. During the upward movement of member 72, float 86 and valve member 82 are carried along with it, leaving the support on the top end of stem 62. Member 82 remains in engagement with seat 76 during the upward movement of member 72 until valve member 84 and valve seat 78 meet, as shown in Fig. 5.

As soon as valve seat 78 has made contact with valve member 84, float 86 drops back to its original position on stem 62, carrying with it valve member 82, which drops away from valve seat 76. This action assumes, of course, that there is insufficient water in valve shell 66 to provide

buoyance to float 86. If enough water were present in shell 66 to support the float, the latter would not drop away. Instead, the valve at 76 would remain sealed. In this position, port 74 is now sealed at its upper end only. It will be noted that through this sequence of operations, port 74 has been closed.

As long as the "on" part of the heating cycle continues with the resulting high pressure, the valve will remain in closed condition, as indicated. However, when the cooling part of the heating cycle begins, the pressure within shell 66 will decrease and on reaching a pressure which may be predetermined through the proper adjustment of stem 62, member 72 will move downwardly away from valve member 84, thereby opening port 74 during the time that member 72 is moving to a position of re-engagement with valve member 82. This condition is shown in Fig. 7.

The period during which port 74 is open is very brief, but during that time a certain amount of air trapped in shell 66 under pressure will escape therethrough and on to the atmosphere through ports 80 and 56.

Each time the heating cycle is repeated, a limited amount of air is vented from shell 66 in the manner just described. The construction is such that more air is vented on each heating cycle than will be distilled from the water in a corresponding time, so that even though the amount of air vented on each cycle is limited, it still vents rapidly enough to always keep ahead of the amount of air that may be trapped. Thus, a radiator containing trapped air will be gradually vented until it is again full of water.

Ultimately the water in the radiator will rise to such a point that it will enter the valve through nipple 42 and rise up within shell 66. When it reaches a certain point in relation to float 86, the latter will become buoyant so that when the valve attempts to go through the cycle of operations heretofore described, the float will fail to drop away from seat 76 following the upward movement of member 72 and engagement of valve seat 78 with valve member 84. In consequence, no further venting of air can take place after water has risen to a point within shell 66 to render float 86 buoyant. That is to say, valve seat 76 is engaged continuously by valve member 82 regardless of the pressure that may exist in the air trapped above the water within shell 66 and bellows 70. If, thereafter, additional air accumulates within the radiator, so that the water level within shell 66 drops, then the venting recommences in the manner heretofore described.

In practice, the pressure that is developed during the heating part of a heating cycle in the upper portion of a radiator containing trapped air may easily be measured and the valve stem 62 set accordingly. That is to say, if it were found on a heating cycle that the maximum pressure reached was 30 lbs., while the minimum pressure during the off part of the cycle was 20 lbs., valve stem 62 will be adjusted upwardly to a point where further elongation of the bellows 70 would not take place until the pressure within shell 66 exceeded the minimum pressure required. As pressure within shell 66 increases, float 86, valve member 82 and movable member 72 all move upwardly as a unit to engage upper valve member 84. When the pressure has increased to a sufficient degree, say, 25 lbs., movable member 72 comes into engagement with

upper valve member 84, sealing passage 74 at its upper end, whereupon float 86 and valve member 82 fall away from seat 76, as shown in Figs. 6 and 10. As long as pressure in excess of that necessary to elongate bellows 70 sufficiently to hold movable member 72 in contact with valve pin 84 is maintained, port 74 will remain sealed by the upper valve. Thereafter, however, when the pressure within shell 66 decreases to slightly less than the elongating pressure of, for example, 25 lbs., member 72, under the contractive tendency of bellows 70, will commence downward movement toward valve pin 82, drawing away from valve pin 84. This condition is shown in Figs. 7 and 11. At once the trapped air under compression will begin to escape through port 74. As this action goes on, resulting in a decrease of pressure within valve shell 66, bellows 70 contracts and member 72 moves downwardly, increasing the space between upper valve member 84 and member 72. When the latter reaches a certain point in relation to valve pin 82, float 86 lifts to drive pin 82 against seat 76, thereby closing port 74 against further egress of air therethrough.

In this manner, limited amounts of air are vented during each cycle. The amount that is vented is determined by the size of the various ports and the pressures under which the valve is set to operate.

It is apparent that the valve may be readily adjusted for use with systems using widely varying pressures and on particular radiators in which the pressures vary in accordance with the elevation.

It is apparent that valve 26 could be directly connected to the radiator by a suitable L fitting, but since at the start of a heating season it is desirable to fill the radiators completely and quickly, we prefer to use a special fitting 28 for the connection, which is shown in Fig. 3.

A broken away section of radiator is shown at 100 having a threaded hole therethrough at 102. Into this hole is screwed the threaded tubular member 104 having a port 106 including a valve seat 108. Connecting with port 106 is an upwardly extending internally threaded connection 110 adapted to receive nipple 42. Screwed in a threaded aperture 112 opposite port 106 is a valve pin 114. It is obvious that when valve pin 104 is screwed inwardly, it will be in engagement with seat 108 to close the port 106. When it is screwed outwardly, port 106 will be opened so that water or air may pass from the interior of the radiator to nipple 42.

In order that the threaded connection with the pin 114 may be water-tight, a packing 116 is provided, maintained in place by a cap 118 in screw-threaded engagement with member 104, as shown. At the commencement of a heating season, the operator will unscrew valve 26 from connection 110, port 106 being closed at this time. Then when water is admitted to the system, valve pin 114 may be unscrewed to vent quickly any air that may be trapped in the radiator. When water appears at connection 110, valve pin 114 will be screwed inwardly to close port 106 to prevent any overflow. Valve 26 is then screwed tightly into position in connection 110 and finally valve pin 114 is unscrewed to open port 106, in which condition it remains for the rest of the heating season. The automatic operation of valve 26 thereafter takes care of any subsequently trapped air.

From the foregoing description of the heat-

ing system and the particular type of venting valve that is used, it will be seen that the method of venting the system comprises first heating the water to cause expansion thereof, which in turn results in compression of the trapped air. This compression in turn, acting on an expandable member, results in a slight increase in the space in which the air is trapped. Thereafter, as the heat is discontinued and the water contracts, thereby commencing a reduction in the pressure of the trapped air, a valve is momentarily and automatically opened to permit the escape of a limited amount of air while the expandable container is returning to its original position of minimum volume.

Thus it will be seen that the method of venting the air is concerned with compressing the trapped gas, expanding the container within which it is held and then reducing the container size while at the same time opening a valve to the atmosphere so that part of the gas will be expelled. Thus, by repetition of these steps, excessive amounts of trapped air are gradually eliminated. It is understood, of course, that the air is eliminated at a rate greater than it is distilled from the water of the heating system.

A modified form of the valve is shown in Figs. 8 to 11. This consists of a base 120 adapted for connection with a radiator on which is mounted a shell 122 carried by a perforated plate 124 fixed in turn to the base by lock nut 126. A screen 128 serves to filter out objectionable substances.

Plate 124 is centrally threaded and screwed therein is adjusting stem 130 on which rests a float 132. Shell 122 has a port 134 to the atmosphere and is closed at its upper end by an internally extending flange 136 soldered or otherwise secured to the shell at 138 and on which is screwed a closure cap 140.

Interiorly threaded to flange 136 is a plug 142 which in turn is centrally threaded at 144 to receive a threaded adjustable valve pin 146. From this construction, it may be seen that upon removal of cap 140, valve pin 146 may be adjusted as the circumstances require.

An annular plate 148 is secured interiorly of the shell 122 by soldering or in any other pressure-tight manner. For the purpose of facilitating assembly, beads 150 and 152 have been provided in shell 122 which enable flange 136 and plate 148 to be quickly and accurately positioned.

Mounted on plate 148 is a bellows 154, to which at the top is secured a valve member 156 having a port 158 therethrough. This valve member has a circular flange 160, the lower rim of which acts as a valve seat 162 for engagement with a valve disk 164, of rubber or other suitable material, carried by a valve plate 166 having a circular flange 168 that corresponds to flange 160. Plate 166 is fixed to a valve stem 170, which in turn is mounted on float 132. The upper end of valve stem 170 terminates in a guide 171.

The upper edge of port 158 serves as a valve seat 172 which may be engaged by valve pin 146. A spring 174 exerts a downward force on valve member 156. The spring pressure may be varied by adjustment of plug 146 so that the pressure within chamber 176 required to elongate bellows 154 may be controlled.

During the non-heating part of the cycle, the valve is in the position shown in Fig. 8. Thereafter, during the heating portion of the cycle, as the heat increases and the pressure in chamber 176 becomes greater, bellows 154 will be elongated and valve member 156 will move upwardly until valve seat 172 comes into engagement with valve pin 146. The lower valve will, of course, remain closed and the condition of the parts at this time is shown in Fig. 9.

Thereafter, the lower valve will open and the air trapped in chamber 176 will be held thereby continued closure of the upper valve. When, however, the heat is discontinued and the pressure recedes sufficiently, bellows 154 will contract, opening the upper valve. When this takes place, both the upper and lower valves will be open so that a limited amount of the trapped air may escape. Finally, the lower valve closes when rim 162 seats again on valve disk 164. This closure may be due either to movement of valve member 156 to its lowermost position, as shown in Fig. 7, or it may be due to a lifting of float 132 from its adjusting stem support. The latter condition can happen if the clearances are so adjusted that the velocity head of the air past the lower valve disk and plate is sufficient to raise the latter to a position to meet the descending valve member 156.

Through proper setting of adjusting stem 130 and valve pin 146, the movement of valve member 156 and the resulting valve opening may be definitely controlled. Similarly, adjustment of plug 146 enables the pressures at which bellows 154 elongates to be set to any figure required by the particular system with which the unit is used.

The provision of the adjustable upper valve pins 84 and 146 makes it possible to manually cause the venting of air from the radiators. Thus, at the beginning of a heating season, when a radiator is likely to contain considerable trapped air, it is possible to vent the radiators in the following manner. Referring to the construction in Figs. 8 to 11, the procedure is this. Cap 140 is removed and a screw driver or other suitable tool is then inserted in the slot in the upper end of the valve pin 146, the latter then being screwed downwardly to engage valve seat 172. As soon as this happens, valve disk 164 will drop away from rim 162, opening the lower valve. Then, by rotating valve pin 146 in the opposite direction to open the upper valve, there will be momentary escape of air through port 156. Immediately thereafter, however, the pressure within the casing and the velocity of gas through the valve will cause float 132 and connected valve disk 164 to move upwardly to seal the lower valve. Valve pin 164 is then screwed downwardly again to close the port at the upper end, whereupon float 132 falls away in the manner previously described. Thus, by repeated up and down movement of valve pin 146, the radiators may be vented. This assumes, of course, that the air in the radiator is under enough pressure to cause venting.

Operation of valve pin 84 in the construction shown in Figs. 2 to 7 would accomplish the same result.

A further modification of the valve structure is shown in Fig. 12, although in general the principle remains the same as those heretofore disclosed.

It will have been observed that, in the construction shown in Figs. 2 to 7 and 8 to 10, the upper valve pins 84 and 146 are manually adjustable with respect to their corresponding upper valve seats. By such adjustment the distance that the members 72 and 156 must move before engagement with the upper valve may be controlled.

The construction of Fig. 12 varies this to the extent that the upward movement of the valve member before engagement with the upper valve pin is limited to a maximum on each cycle of operation. This will become more apparent as the description proceeds.

The casing 180 houses the valve mechanism the same as the previously described casings 66 and 122. An expansible bellows 182 is secured therein, being closed at its top by the valve member 184 having a port 186 therethrough. At the lower end of the port is a valve seat 188 and at the upper may include a seating member 192 to form a end a valve seat 190. The lower valve seat 188 tighter seal with valve member 184 mounted on a float 196 similar to the floats heretofore described. Lower valve seat 188 is normally in engagement with valve 194 during the cooling part of the heating cycle, as the contractive force of bellows 182 is sufficient to hold it in such position.

Mounted on the valve member 184 by screw threaded connection is a cap 198 centrally perforated at 200 and having side ports 202 and 204.

Extending downwardly into the confines of cap 198 is a valve member 206 having a valve seat engaging head 208. This head is somewhat larger than the perforation 200 so that downward movement of cap 198 will cause engagement of the cap flange and valve head 208.

Valve member 206 is maintained in position by a pair of shoes 210 and 212 which frictionally engage the sides of the valve stem. These shoes are urged toward the valve stem by springs 214 and 216 maintained in position by spring holders 218 and 220. The force of the springs 214 and 216 against the shoes is sufficient to hold valve stem 206 against movement except as upward or downward force is applied to it through movement of valve member 184.

The operation of this construction is as follows. During the heating portion of the cycle, as the pressure increases within the casing, bellows 182 is elongated, moving valve member 184 upwardly, but port 186 remains closed because the pressure conditions that prevail within the lower part of the casing cause float 196 and attached valve 194 to remain in engagement with valve member 184 during the latter's upward movement. In due course, the upper valve seat 190 will engage valve pin head 208 and thereafter, if further upward movement of valve member 184 takes place, valve stem 206 will slide upwardly between shoes 210 and 212.

As soon as the upper end of port 186 is closed, valve 194 will drop away, as in the case of the other forms, the valve remaining sealed by the upper valve pin only. Thereafter, as the pressure in the system decreases, valve member 184 will drop away from valve 208, which is held tightly enough by shoes 210 and 212 to allow such action, thereby permitting the instantaneous escape of gas through ports 202 and 204 to the atmosphere through casing port 222. This instantaneous escape takes place while both valves 194 and 208 are out of engagement with their respective seats on valve member 184. When the contraction of bellows 182 has proceeded far enough, cap 198 will engage valve head 208, thereby drawing the upper valve downwardly as further reduction of pressure in the valve occurs. It is believed obvious that when this condition has set in, the distance 70 between valve head 208 and valve seat 190 will have reached a maximum and will thereafter remain constant. That is to say, when upward movement of valve member 184 commences on each succeeding cycle, the distance valve seat 190

must move before engagement with valve head 208 will be uniform, and thus closure will take place after valve member 184 has moved the necessary predetermined distance, and further adjustment will be unnecessary.

We claim:

1. An air venting valve of the class described comprising a casing having an inlet adapted for connection with the system with which it is to be used and a port leading to the atmosphere, said port being formed by an aperture through a movable member connected to said casing by pressure movable means, a valve member mounted within said casing and normally in engagement with said movable member to close said port, means for moving said valve member upwardly with said movable member when the latter is displaced under conditions of increasing pressure within said casing, a second valve member positioned for engagement with said movable member to close said port when said movable member has moved upwardly a predetermined distance from its normal position, the construction being such that said first valve member will return to its original position following closing of said port by said second valve member so that said port will be momentarily opened during return movement of said movable member from its upper closed position against said second valve to normal closed position against said first valve member.

2. A valve for venting air from a hot water system in which the water is heated intermittently, comprising a casing having an inlet and a port to the atmosphere, said casing including a movable portion having a member with an aperture therethrough affixed thereto, a valve member within said casing and normally in engagement with said movable member to close said aperture under conditions of low pressure and in the absence of water in said casing, said valve member supported against downward movement from its normal position but capable of movement upwardly with said movable member and a second valve member positioned above and normally out of engagement with said movable member, the movable portion of said casing being capable of sufficient motion to permit said movable member to be forced into engagement with said second valve member upon the application of sufficient pressure within said casing, the construction being such that said first valve member will return to its original position following closing of said aperture by said second valve member so that said aperture will be momentarily opened during return movement of said movable member from its upper closed position against said second valve member to normal closed position against said first valve member.

3. A valve for venting air from a hot water system in which the water is heated intermittently, comprising a casing, a first valve member limited in its downward movement and capable of upward movement, a second valve member maintained in fixed position, a movable member having an aperture therethrough and normally in engagement with said first valve member to close said aperture, said first valve member and said movable member capable of joint movement under the influence of sufficient pressure within said casing toward said second valve member until the latter has closed said aperture by engagement with said movable member, the construction being such that said first valve member will return to its original position following closing

of said aperture by said second valve member so that said aperture will be momentarily opened during return movement of said movable member from its upper closed position against said second valve member to normal position with respect to said first valve member.

4. A valve for venting gas from a hot water system in which the water is heated intermittently, comprising a casing divided into upper and lower spaces by a bellows, said bellows having mounted thereon an apertured member through which gas may pass from the lower to the upper space, a port from the upper space of said casing to the atmosphere and means for connecting the lower space of said casing to said system, a float supported within the lower area of said casing and having mounted thereon a valve member, said float and valve member being free to move upwardly under suitable conditions of gas pressure or water level within the lower space of said casing while continuously in engagement with said apertured member to prevent the passage of gas from the lower to the upper space, and a second valve member located closely above said apertured member in fixed relation to said casing and adapted to engage and close said apertured member when the latter has moved upwardly thereagainst, the construction being such that immediately upon engagement of said apertured member and said second valve member and when insufficient water is in the casing to hold said first valve member closed, said first valve member and float will fall away thereby opening said apertured member on the lower side.

5. Valve mechanism for use in a valve for venting air from a hot water system in which the water is heated intermittently, comprising a bellows, a valve member connected thereto and having an aperture therethrough, one end of said aperture terminating in an annular valve seat larger than said aperture, the other end of said aperture terminating in a valve seat smaller than said annular valve seat, a valve for engaging said annular valve seat comprising a valve disk and an upwardly extending guide long enough to enter said aperture without closing the aperture to the flow of air, and a valve for engaging said second valve seat comprising a valve pin, and means for supporting said valves, said first valve being movable toward and away from said second valve.

6. An air venting valve as set forth in claim 1, having means for varying the resistance of said pressure movable means to the influence of pressure developed within said casing.

7. A valve as set forth in claim 2, having spring means for exerting a force against said apertured member in the direction of said first valve member.

8. A valve for venting compressed air, comprising a casing, a first valve member within said casing, a stop for limiting the downward movement of said first valve member, a second valve member maintained in adjustable relation to said casing, a movable member closing said casing positioned between said first and second valve members having an aperture therethrough, said aperture arranged to be completely closed by either of said valves, the area of said aperture bearing such relationship to said first valve member that the latter will be driven upwardly to close said aperture immediately following the escape of gas from said casing under pressure conditions that normally prevail therein, and that the first valve member will fall away from

said closed position when the aperture is closed at its other end by said second valve member.

9. A valve for venting compressed air from a hot water heating system capable of either manual or automatic operation, said valve comprising a casing, a first valve member movable upwardly, a member closing said casing and movable under varying pressures within said casing, said member having a single aperture therethrough adapted to be closed completely by said first valve member when in engagement therewith, a second valve member positioned opposite said first valve member and adapted to close completely said aperture in said movable member when the latter has been brought into engagement therewith, the area of said aperture bearing a relationship to said first valve member such that under conditions of increased pressure that may prevail in said casing, said first valve member will be raised from its seat to close said aperture, said second valve member manually adjustable with respect to said aperture, the construction being such that said aperture may be closed by said second valve by either an increase of pressure within said casing sufficient to drive said movable member against said second valve member or by manually moving said second valve member into engagement with said movable member, the relationship of all the parts being such that whenever said aperture is closed by said second valve member, said first valve member will fall away from said movable member to open the inner end of said aperture.

10. A valve for venting air from a hot water heating system, as set forth in claim 9, in which said first valve member is mounted on a float whereby said aperture will be continuously closed by said first valve member after water has risen within said casing a distance sufficient to render said float buoyant.

11. A valve for venting air from a hot water system in which the water is heated intermittently, comprising a casing having an inlet and a port to the atmosphere, said casing including a movable portion having a member with an aperture therethrough affixed thereto, a valve member within said casing and normally in engagement with said movable member to close said aperture, said valve member limited in its downward movement from its normal position but capable of movement upwardly with said movable member, and a second valve positioned above and normally out of engagement with said movable member, the movable portion of said casing being capable of sufficient motion to permit said movable member to be forced into engagement with said second valve member upon the application of sufficient pressure within said casing, said second valve member movable upwardly after engagement with said movable member upon further upward movement of the latter, and means connected to said movable member for drawing said second valve member downwardly after said movable member has fallen away from said second valve member a predetermined distance.

12. A valve as set forth in claim 2, in which the second valve member is movably maintained in position to permit upward and downward movement thereof under the influence of said movable member.

13. A valve as set forth in claim 2, in which said second valve member is movably maintained in position whereby it may move upwardly after engagement with said movable member, and

means associated with said movable member whereby said second valve member may be drawn downwardly upon downward movement of said movable member after the latter has fallen away a predetermined distance from said second valve member.

14. A valve for venting air from a hot water system in which the water is heated intermittently, comprising a casing, a first valve member limited in its downward movement and capable of upward movement, a second valve member maintained in fixed position in alignment with said first valve member, a movable member having an aperture therethrough and positioned between said first and second valve members, said aperture adapted to be completely closed upon engage-

ment of said member with either said first or second valve member, said movable member adapted to engage said first valve member under conditions of relatively low air pressure in said casing to close said aperture, said first valve member and said movable member capable of joint movement under the influence of increasing air pressure within said casing toward said second valve member until the latter has closed said aperture by engagement with said movable member, said first valve member constructed to fall away from said movable member immediately upon closure of said aperture by said second valve member.
